UNITED STATES PATENT OFFICE

130,834

DESIGN FOR A MOTOR CASING

Frank J. Woods, Wilmette, Ill., assignor to
Conrad D. Mastrud, Oak Park, Ill.

Application March 29, 1941, Serial No. 100,006

Term of patent 14 years

To all whom it may concern:

Be it known that I, Frank J. Woods, a citizen of the United States, residing at Wilmette, in the county of Cook and State of Illinois, have invented a new, original, and ornamental Design for a Motor Casing, of which the following is a specification, reference being had to the accompanying drawing, forming a part thereof.

Fig. 1 is a front elevational view of a motor casing showing my new design;

Fig. 2 is a side elevational view of the motor casing, the sides of the casing being similar; and
Fig. 3 is a top plan view.

I claim:

The ornamental design for a motor casing, substantially as shown and described.

FRANK J. WOODS.
